John Oliver Creek, Brampton, Ontario, Canada, assignor to A. V. Roe Canada Limited, Malton, Peel, Ontario, Canada, a corporation

Application December 29, 1953, Serial No. 400,913

4 Claims. (Cl. 78—60)

This invention relates to forging, stamping, blanking, forming, and like presses, and more particularly to a novel die holding structure therefor.

It is the usual practice in such presses to mount a punch or upper die rigidly on the reciprocatable ram of the press, and a lower die rigidly on the oppositely disposed bolster plate. It is generally necessary to provide some form of guide, such as pins and bushes, or keys and keyways, which come into engagement as the ram is moved towards the bolster plate and serve to direct the two dies into accurate registration. These guides are provided with generous leads to facilitate engagement; the working clearances in the slideways of the ram are relied upon to accommodate any transverse displacement of the upper die in the process of registration with the lower die. It is unavoidable that wear will take place between the engaging surfaces of the guides, because of the inertia of the comparatively large mass of the ram and of the die secured to it, which inertia tends to resist the transverse forces exerted by the guides.

Furthermore, it is usually expedient to locate the guides at some distances from the dies; the necessary working clearances of the guides, and any subsequent wear therein, are consequently correspondingly magnified in the resulting inaccuracy of registration of the dies.

An object of the invention therefore is to provide a construction which permits the ready and accurate registration of the dies in a press without causing excessive wear on the guides.

Another object of the invention is to provide a press construction in which the guides are located as closely as possible to the dies.

The foregoing and still further objects and advantages of the invention will become apparent from a study of the following specification, taken in conjunction with the accompanying drawings, in which like reference characters indicate corresponding parts throughout the several views and in which:

Figure 1 is a perspective view showing a conventional forging press bolster plate on which a die is mounted in accordance with the invention.

Figure 2 is a cross-sectional view taken through the line 2—2 of Figure 1 and showing in addition a ram and its associated die constructed in accordance with the invention;

Figure 3 is a cross-sectional view taken through the line 3—3 of Figure 1 and showing in addition the ram and the associated die; and

Figure 4 is a top plan view of the lower die and its associated shroud.

Referring to the drawings, there is illustrated the conventional bolster plate member 11 of a typical forging press and the equally conventional oppositely disposed reciprocatable ram member 12 which is movable towards and away from the bolster plate member during a forging operation. A base 13 (and the hereinafter described components mounted on it) is firmly secured to either of the members; in the drawings it is shown as being

secured to the bolster plate member 11 by means of a stud and nut assemblies 14.

A channel 15 is provided by recessing a portion of the surface of the base relative to the contiguous portions 16 on each side thereof, the bottom of the channel being inclined relative to the surfaces of the contiguous portions 16. Slidably mounted within the channel is a wedge member 17 having a major surface 18 which is complementary to the inclined surface of the channel when its opposite major surface 19 is parallel to the surfaces of the contiguous portions 16 of the base. The thicker end of the wedge member 17 protrudes from the channel and carries a flange 20 which overlaps the adjacent end face of the base. Longitudinal adjustment of the wedge member in the channel may be effected by means of a set screw 21 which is threaded in the flange 20 and engages the adjacent end face of the base, and by means of opposing lock nuts 22 threaded on studs 23 which extend from the aforesaid end face and pass through clearance holes in the flange 20. It will be appreciated that by altering the longitudinal adjustment of the wedge in the channel the height of its major surface 19 relative to the contiguous portions 16 of the base may be varied.

Supported on the contiguous portions 16 of the base 13 and bridging the recessed portion or channel 15 is a shroud 24. The shroud is so mounted on the base that it is held in engagement therewith whilst it is free to slide thereon. As may be seen particularly in Figures 1 and 3 grooves 25 are provided in the side faces of the shroud, and these are engaged by flanges or keepers 26 secured to the base. The keepers permit some degree of lateral movement and unlimited longitudinal movement between the shroud and the base, but they securely hold the shroud against the base. Longitudinal movement of the shroud is limited by stop pins 27 which extend from the base and are adapted to engage the end faces of the shroud. Preferably the keepers and the stops are set to permit movement of the shroud relative to the base of $\frac{1}{8}$ " in any direction.

Extending through the shroud in the portion thereof which is opposite the channel in the base, is an opening defined by side walls 28. Securely held therein against movement in any direction parallel to the base is a die 29 of conventional construction, comprising a substantially rectangular steel block having an impression 30 of the part to be forged sunk in its upper face. The die is restrained against movement by plates 31 and wedges 32. The plates and wedges are disposed between the perimetrical walls of the die and the adjacent walls 28 of the opening, each plate being opposed by a wedge. The opening is not accurately rectangular in plan view; its walls in contact with the wedges are complementary to the wedges. Thus, the die 29 is held squarely between the wedges 32 and the plates 31 when the wedges are driven home. The corners of the opening are relieved, as indicated for example at 33 in Figure 1, to accept a taper drift whereby the wedges may be driven in or out.

The plates 31 and the wedges 32 are provided with generous radii along their inner upper edges 31a and 32a respectively, and with externally extending flanges 31b and 32b respectively along their outer upper edges to engage the contiguous portions 16 of the shroud.

The die 29 is supported on the base by means of the wedge member 17. Thus, the wedge member prevents movement of the die in a direction normal to the plane of the base. Since the shroud 24 is not required to provide any support for the die it can be of relatively light construction. It should also be noted that the height of the die measured from the plane of the base 13 and normal thereto is less than the height of the shroud similarly measured; so that the side walls 28 of the opening

and likewise the plates 31 and the wedges 32 which line the side walls extend above the die.

The ram 12 of the press carries a rigidly mounted upper die 34 of conventional construction. The outer plan form of the die 34 is similar to the outer plan form of the die 29, and therefore the plates 31 and the wedges 32 which line the side walls 28 of the opening in the shroud define an opening or female element which is at least in part complementary to the die 34; relative to the said opening, the die 34 provides a male element. The perimetrical walls of the die 34 are slightly relieved so that, as the ram descends, the die 34 will slidably enter the opening defined by the plates and the wedges. Thus, complementary means associated with the dies 34 and 29, namely, the perimetrical walls of the die 34 in co-operation with the plates and the wedges which define the opening in which is held the lower die 29 provide guides for the accurate registration of the two dies; no other guide is required.

To set up the lower die 29 on the forging press, it is first mounted in the opening in the shroud 24 by means of the plates 31 and the wedges 32 to form a unit which for convenience is referred to as the die assembly. The base 13 with the die assembly supported on it is then located on the bolster plate 11 in a position which will allow the upper die 34 to enter easily into the space defined by the plates and the wedges when the shroud 24 is substantially centrally disposed between the two stop pins 27 and between the two keepers 26. The bolts 14 are then tightened.

The height of the die 29 is adjusted by then loosening the wedges 32 and adjusting the set screw 21 and the lock nuts 22 until the required height is obtained. The wedges 32 are then driven into the locked position again.

During the forging operation the upper die enters the opening defined by the plates and the wedges, and any misalignment between the two dies which will be present is accommodated easily by a sliding movement of the die assembly on the base under the guiding influence of the rounded edges 31a and 32a of the plates and of the wedges. Due to the comparatively small mass of the die assembly, the inertia loads imposed upon the plates and the wedges will not be very high and therefore will not cause any appreciable wear. Accurate registration of the upper and lower dies will therefore be maintained over a long period of use. Lifting of the shroud 24 during retraction of the ram is prevented by the keepers 26 which, as hereinbefore stated, are so arranged in the grooves 25 of the shroud so as to resist any movement of the shroud relative to the base in a direction normal to the plane of the base.

Since by the construction described, provision is made for a sliding movement of the relatively light lower die assembly, the ram of the forging press is not required to accommodate any misalignment of the two dies. This reduces wear of the slideways of the press and permits smoother operation than has heretofore been possible.

It is to be understood that the form of the invention herewith shown and described is to be taken as a preferred example of the same, and that various changes in the shape, size and arrangement of the parts may be resorted to without departing from the spirit of the invention or the scope of the subjoined claims.

What we claim as our invention is:

1. In a press having a bolster plate member and an oppositely disposed reciprocatable ram member movable towards and away from the bolster plate member, a base rigidly secured to one member, a portion of the surface of the base being recessed relative to the contiguous portions on either side thereof, the recessed surface being inclined relative to the surfaces of the contiguous portions, a shroud supported on the said contiguous portions of the base and bridging the recessed portion, restraining means on the said contiguous portions of the base and coupled to the shroud to hold it in

engagement with the base whilst permitting sliding movement of the shroud on the base, an opening defined by side walls being provided in the portion of the shroud disposed opposite to the recessed portion of the base, a wedge member having a major surface complementary to the inclined recessed portion of the base and an opposite surface parallel to the surface of the said contiguous portions of the base, means for adjustably positioning the wedge on the recessed portion of the base to thereby vary the height of its aforesaid opposite surface relative to the aforementioned contiguous portions of the base, a first die supported on the aforesaid opposite surface of the wedge, the said die being accommodated in the opening in the shroud and securely held therein against movement in a plane parallel to the plane of the aforesaid contiguous portions of the base, a second die including a male element secured to the other member, the male element being at least in part complementary to the opening, the male element slidably engaging the side walls of the opening to slidably move the shroud and the first die on the base and to enable the dies to register as the ram member is moved towards the bolster plate member during normal operation of the press.

2. A die structure for use in a press having a bolster plate member and an oppositely disposed reciprocatable ram member movable towards and away from the bolster plate member, the structure comprising a base for rigid attachment to one member, a first die mounted on the base with freedom of sliding movement in directions normal to the direction of movement of the ram member relative to the bolster plate member, restraining means securely holding the said die in engagement with the base whilst permitting said sliding movement of the said die on the base, a second die for rigid attachment to the other member, a male element associated with the second die and a female element associated with the first die and with which the male element is adapted to slidably engage, the engagement of the two elements causing the aforesaid sliding movement of the first die on the base so that the dies mutually register as the ram member is moved towards the bolster plate member during normal operation of the press.

3. A die structure for use in a press having a bolster plate member and an oppositely disposed reciprocatable ram member movable towards and away from the bolster plate member, the structure comprising a base for rigid attachment to one member, a shroud mounted on the base with freedom of sliding movement in directions normal to the direction of movement of the ram member relative to the bolster plate member, restraining means securely holding the shroud in engagement with the base whilst permitting said sliding movement of the shroud on the base, the shroud having an opening defined by side walls, a first die accommodated in and securely held in the shroud opening, a second die including a male element for rigid attachment to the other member, the male element of the second die being at least in part complementary to the opening in the shroud, the male element being adapted to slidably engage the side walls of the opening to slidably move the shroud together with the first die on the base in the aforesaid normal directions and to enable the dies to register as the ram member is moved towards the bolster plate member during normal operation of the press.

4. A die structure for use in a press having a bolster plate member and an oppositely disposed reciprocatable ram member movable towards and away from the bolster plate member, the structure comprising a base for rigid attachment to one member, a first die supported on the base, a shroud having a face which bears on the base and having an opening defined by side walls and in which the first die is encompassed and firmly secured, the first die and the shroud together having freedom of sliding movement on the base in directions normal to the direction of movement of the ram member relative to the

bolster plate member, restraining means securely holding the shroud and the first die in engagement with the base whilst permitting said sliding movement of the shroud and the first die on the base, the first die being disposed below the plane of the face of the shroud which is opposite the face which bears on the base so that the side walls of the opening extend above the first die, a second die including a male element for rigid attachment to the other member, the male element being at least in part complementary to the aforesaid opening, the male element being adapted to slidably engage the side walls of the opening to move the shroud and the first die on the base in the aforesaid normal directions and to enable the dies to register as the ram member is moved towards the bolster plate member during normal operation of the press.
